WATERTIGHT BOX CONNECTER

Paul N. Dann, New Haven, Conn., assignor to
 The Rattan Manufacturing Company, New
 Haven, Conn., a corporation of Connecticut

Application November 1, 1935, Serial No. 47,808

1 Claim. (Cl. 247—18)

This invention relates to improvements in water-tight connectors for electric-connection boxes.

One object of this invention is to provide an improved water-tight connector for electric-connection boxes which will effectively prevent the entrance of water past the cable and into the box.

Another object of this invention is to provide an improved water-tight connector formed of simple elements readily manufactured and readily assembled to produce a durable efficient construction at minimum cost.

With the above and other objects in view, this invention includes all improvements over the prior art which are disclosed in this application.

In the accompanying drawing, in which certain ways of carrying out the invention are shown for illustrative purposes:

Fig. 1 is a front elevation illustrating a water-tight connector made in accordance with this invention applied on a portion of a connection-box;

Fig. 2 is a right-side elevation of Fig. 1;

Fig. 3 is a rear elevation of Fig. 1, with the connection-box omitted;

Fig. 4 is an enlarged sectional view on line 4—4 of Fig. 1;

Fig. 5 is a perspective view of the clamping-hood;

Fig. 6 is a perspective view of the compression-member;

Fig. 7 is a perspective view of one form of sealing-member; and

Fig. 8 is a perspective view of another form of sealing-member.

In the description and claim, the various parts are identified by specific names for convenience, but they are intended to be as generic in their application as the prior art will permit.

Referring to the drawing, 10 is a plate or part of an electric-connection box which is provided with an internally-threaded cable-hole 11 therethrough. 12 is a compression-member or bushing having a cable-hole 12^a therethrough and an externally-threaded portion 13 adapted to threadedly engage in the threaded opening 11. The compression-member 12 at its opposite end has a continuous end-flange or compression-flange 14 and a pair of ears 15, each having a threaded hole therethrough. A clamping-hood 16 is preferably made hollow or concave, as shown, and has fitting therein a sealing-member 17 of readily deformable material, preferably elastic material such as soft rubber or the like. Clamping-hood 16 has a cable-hole 16^a therethrough.

Screws or bolts 18 extend through ears 19 formed on the clamping-hood 16 and threadedly engage in the threaded ears 15 of the compression-member 12. By adjusting the screws 18 to the desired degree, the sealing-member 17 is crowded or compressed and caused to seal water-tight, the area between the sealing-member 17 and the surface of the cable 20, and the area between the sealing-member 17 and the compression-flange 14 of the compression-member 12, thus preventing the entrance of water to the interior of the compression-member 12.

The threaded joint 11, 13 can readily be made water-tight in any suitable well-known way, as by means of white lead or equivalent material. Thus, all possible paths for the entrance of water past the wall 10 and to the interior of the box are rendered water-tight against the entrance of such water. It will be appreciated that the compression-member 12 may be connected in water-tight fashion in any other suitable manner to the wall 10.

The sealing-member 17 has an elliptical cable-hole 21 therethrough to conform to elliptically-shaped cables when they are used. But where a round cable is used, a slightly-different sealing-member 22 is employed, in which a cable-hole 23 of round form is provided to make proper sealing contact with a round cable extending therethrough. Either of these sealing-members 17 or 22 may be used in the same connector, as the outside contour of both sealing-members is the same and fits in the cavity of the clamping-hood 16.

The invention may be carried out in other specific ways than those herein set forth without departing from the spirit and essential characteristics of the invention, and the present embodiments are therefore to be considered in all respects as illustrative and not restrictive, and all changes coming within the meaning and equivalency range of the appended claim are intended to be embraced therein.

I claim:

A water-tight connector for electric-connection boxes comprising: a hollow clamping-hood having a cable-hole therethrough, a flange at one end, a pair of ears spaced back from the front edge of said flange, and slots in and extending through the front edge of said flange in front of said ears; a sealing-member of readily-deformable material and having a cable-hole therethrough and adapted to fit in said clamping-hood; a compression-member having a cable-hole therethrough, a compression-flange adapted to fit 55

- within the flange of said clamping-hood, and a pair of ears adapted to fit within said slots, said compression-member being adapted to be connected to a plate of a box provided with a cable-hole through the plate and with said sealing-member between said clamping-hood and said compression-member and with said cable-holes of the clamping-hood, sealing-member, compression-member and plate in general alignment; and 5
10 adjustable clamping-bolts threadedly connecting the ears of said clamping-hood and compres-

sion-member and adapted to be adjusted to compress said sealing-member between the clamping-hood and the compression-flange of the compression-member and cause said sealing-member to seal water-tight, the area between said sealing-member and a cable extending through the cable-hole of the sealing-member and the area between said sealing-member and the compression-flange of the compression-member surrounding the cable-hole through the compression-member. 10

PAUL N. DANN.
